ROUGHING AND FINISHING CENTER DRIVE LATHE

George A. Kendall and Alex W. Chriscaden, Saginaw, Mich., assignors to Wickes Bros., Saginaw, Mich.

Application April 6, 1950, Serial No. 9,006

Term of patent 14 years

(Cl. D54—6)

To all whom it may concern:

Be it known that we, George A. Kendall and Alex W. Chriscaden, both citizens of the United States of America and residents of Saginaw, in the county of Saginaw and State of Michigan, have invented a new, original, and ornamental Design for a Roughing and Finishing Center Drive Lathe, of which the following is a specification, reference being had to the accompanying drawing, forming part thereof.

In the drawings:

Fig. 1 is a perspective view showing the front and one end of a roughing and finishing center drive lathe embodying our new design.

Fig. 2 is also a perspective view showing the front and the opposite end of the lathe.

Fig. 3 is a perspective view showing the rear and one end of the lathe.

Fig. 4 is a view slightly in perspective taken from the end opposite that shown in Fig. 3.

We claim:

The ornamental design for a roughing and finishing center drive lathe, as shown.

GEORGE A. KENDALL.
ALEX W. CHRISCADEN.
